UNITED STATES PATENT OFFICE.

SYLVENUS WALKER, OF BOSTON, MASSACHUSETTS.

INKSTAND AND PEN-RACK.

Specification forming part of Letters Patent No. 37,313, dated January 6, 1863; antedated July 6, 1862.

To all whom it may concern:

Be it known that I, SYLVENUS WALKER, of Boston, in the county of Suffolk and State of Massachusetts, have invented a new and Improved Inkstand and Pen-Rack Combined; and I do hereby declare the following to be a full, clear, and exact description of the same, reference being had to the accompanying drawings, making a part of this specification, in which—

Figure 1 represents my invention by a perspective view. Fig. 2 is a vertical central section, $\alpha\alpha$ of Fig. 1 indicating the plane of section. Fig. 3 is a similar view of my invention in a position for filling.

Similar letters of reference indicate corresponding parts in the several figures.

The object of this invention is to obtain a simple, unique, and economical device that will serve as an inkstand and pen rack combined.

To enable others skilled in the art to fully understand my invention, I will proceed to describe it.

A represents the dipping-cup, of circular form, and B a reservoir of an inkstand formed wholly of glass. The reservoir, which is on top and at the back of the dipping cup, is of hexagonal shape and of gradually-tapering form toward the top, where it terminates in three horizontal and parallel grooves, $a b c$, the middle groove being above the other two and bisecting the reservoir in a line parallel with the front face of the same, forming a convenient pen-rack, as shown clearly in Fig. 1, capable of holding three pens at a time, and admitting of either one being removed and replaced without liability of displacing the others. The dipping cup in front of the reservoir has projecting from it a small neck, C, which is of spherical form on top and has an aperture, e, in the front side of it, which serves as the dipping-place for the pen, and also as the mouth or orifice to fill the reservoir. The neck of the dipping-place is arranged entirely within the circumference of the dipping-cup,

and at its top and back side is brought over the aperture in the form of a hood, f, as shown in Figs. 1 and 2, to facilitate the operation of filling the reservoir and dipping-cup. (Shown in Fig. 3 in a position for being filled.) The neck C is straight up in front and extends a short distance above the upper surface of the dipping-cup. The ink is prevented from overflowing this neck by the pressure of the atmosphere upon it, precisely the same as in the ordinary atmospheric inkstand. The bottom E of the dipping-cup is convex on its inner side to prevent the pen from being dipped too far into the ink when put in at any angle, thus obviating an objection to all other atmospheric inkstands.

One advantage possessed by this invention over others of a similar character is that the inkstand can be blown into the proper shape to form a pen-rack and inkstand combined, only requiring a little grinding at the mouth of the neck to be ready for the market, thus greatly reducing the cost of manufacture and making a stronger and better-finished article.

The pen-rack at the top is a great convenience and answers precisely as well as the metal appendages hitherto used for the purpose, and which appreciably augment the cost of an inkstand.

The invention is admirably adapted for schools.

Having thus described my invention, what I claim as new, and desire to secure by Letters Patent, is—

1. A fountain-inkstand and pen-rack combined, all made of one piece of glass.
2. In combination therewith, the horizontal grooves $a b c$, reservoir B, dipping-cup A, convex bottom E, neck C, aperture e, and hood f, when combined and arranged as described, for the purposes set forth.

SYLVENUS WALKER.
